UNITED STATES PATENT OFFICE

FRED M. GILMORE AND STEVE FRENCH, OF SEATTLE, WASHINGTON

TURNING LATHE

Application filed June 2, 1927. Serial No. 195,881.

Our invention relates to turning lathes which are designed for automatically shaping blanks into forms of circular cross section such as are customarily produced by turning operations.

Our object is to produce a lathe capable of doing such work in an effective and rapid manner. The lathe, as illustrated, secures such results, and it is believed to employ novel methods and apparatus, and the preferred form of construction illustrated in the drawings will be hereinafter described, and the novel features thereof defined by the claims which terminate this case.

15 Figure 1 is a top or plan view of the lathe; Figure 2 is a rear side elevation of the central zone of the lathe, in which zone most of the operating parts are found;

Figure 3 is a transverse sectional elevation taken through the tool holder carriage, being on line 3—3 of Figure 1;

Figure 4 is a similar transverse sectional elevation, but to one side of the carriage, or on the line 4—4 of Figure 1;

25 Figure 5 is a side elevation showing the tool-holding carriage and the blank-dogging or holding mechanism at the tail end of the lathe in longitudinal section;

Figure 6 is a plan view showing the tail 30 dog and its operating means in partial section;

Figure 7 is a plan view showing the cam mechanisms by which the tool carriage mechanisms are controlled;

25 Figure 8 shows in detail clutch mechanism employed for alternately and oppositely engaging the tool carriage with the opposite runs of the continuously-operating feed chain;

40 Figure 9 shows in perspective the chain-engaging dog or clutch block;

Figure 10 shows a sectional plan taken through the carriage and tool holder on the line 10—10 of Figure 4;

45 Figure 11 is a transverse sectional elevation taken on a plane indicated by the line 11, 11 of Figure 2, illustrating the blank-feeding means and the means for adjusting the same for blanks of different sizes;

50 Figure 12 indicates a modified construction

for the chain clamp member shown in Figure 9, in which roller-clamping elements are employed;

Figures 13 and 14 show consecutive steps in the setting of the driving center.

The particular work for which this machine has been designed is the turning of wood blanks to form such articles as chair legs, banister bars, and other analogous products which vary from a uniform cylindrical shape.

The object sought is a machine which will do this work automatically, requiring manual attention only to the extent of supplying the blanks to a feed chamber or hopper.

The frame 1, which may be of any suitable construction, has a head stock 10 and tail stock 11, the latter movable lengthwise of the bed frame upon suitable guideways, as 12, to adjust for different lengths of work. These parts may be of any suitable type of standard construction.

The head stock has a work-engaging and turning dog 13, and the tail stock a complementary dog 14. The former is turned through any suitable mechanism, that illustrated employing change-speed or step pulleys 15, 16 mounted respectively upon the head stock and upon a driving shaft, and connected by a belt 17. The pulleys 16 are shown as upon the shaft of an electric motor 18, but may be upon a shaft driven in any other suitable manner.

The tail stock 11 has its center dog 14 journaled to freely turn and to be reciprocated, as may be required, for releasing and securing the blank in place. The tail dog is at one end of the shaft 14, which is rotatable in bearings 21 carried by a sleeve 2 mounted to be reciprocated but not turned in a guiding chamber 19, carried by the tail stock. Caps 20

serve to close the sleeve 2. A spring 22 contained within an extension of the chamber 19 normally holds the sleeve 2 and the tail dog in extended working position. A bolt 23 serves to regulate the tension upon the spring 22.

At one side of the sleeve complementary grooves in sleeve 2, and in the wall of its enclosing chamber, receive a thrust bar 24 (see Figure 6), which engages the shoulder at the

bottom of the groove to thereby actuate the sleeve for retractile movement. The outer end of bar 24 is engaged by a rock arm 25 fixed upon a shaft 26 journaled in transverse position upon or in the tail stock. Preferably, the arm 25 carries a roller 25' which engages the end of bar 24. At suitable intervals the shaft 26 is rocked, by means hereafter described, to push back the tail dog, thereby releasing the work, and to permit its projection to engage a new piece.

The work turning tools are carried by a carriage 3, mounted to slide upon a guideway 30 at the front side of the lathe bed. Upon 15 a similar guideway 31 at the opposite side of the bed is mounted a carriage 4 which carries the dogging means, by which driving engagement is alternately made with opposite runs of the carriage-driving chain 40. This chain passes over suitable sprocket wheels 41 and 41' at the ends of the bed, the wheel 41 at the tail end being the driver and being, in turn, driven from any suitable source, that shown being a separate motor 400. The movement 20 of this chain is at all times in the same direction and at a uniform rate, which rate may, however, be changed by adjustment.

Carriage 4, shown in face view in Figure 2, and in end elevation in Figures 3 and 4, 25 carries the chain-gripping dogs or clutch, and the means for operating them, and also the means for controlling the action of the cams by which the cutting tools are controlled. The chain-gripping device is shown in Figure 8 and the gripping block separately in Figure 9, with a modified construction of the latter in Figure 12.

The frame of the carriage has an upper and a lower ledge or projecting flange 42, 40 which each holds in place a thrust and wear block 43, along the inner faces of which pass the two runs of the feed chain 40. The gripping block which fits between the two runs of the feed chain, consists of a plate or web 45 45 and upper and lower blocks 46, which by their exterior faces engage the inner faces of the chain. The adjacent and opposed faces of the blocks 46 are inclined lengthwise relative to their outer faces, thereby producing a wedge effect. These faces of the two blocks are, however, parallel.

In the preferred form of construction for the chain clutch, shown in Figure 12, the two blocks 46 are hollowed or recessed upon 55 their inner gripping faces, and rollers 46' are placed loosely in the recessed runway thus formed. By their use, friction between the block 47 and blocks 46 is minimized and more dependable working is secured.

Fitting between the opposed faces of blocks 46 is a bar 47, from the outer face of which projects a pin 48 which is pivoted in the upper end of a lever 5, (Figure 2), the latter being pivoted at 50 to the cover plate 49

of the carriage. The lower end of lever 5 carries a roller 51 which engages the upper face of lever 52 pivoted at 52' to the carriage cover plate 49. Lever 52 is held upward by a spring 54 and has a tooth 53 which cooperates with a roller 51 carried by lever 5 to insure holding lever 5 in either of two adjusted positions until sufficient force is applied to overcome this resistance.

Pivoted upon the same pivot 50 as is the lever 5, is a throw lever 55 which has a slot or opening 59 through which passes the pin 48, thereby permitting free swinging of the lever 55 through a determined central portion of its path without affecting said pin 48 or the lever 5. A spring 57 holds lever 55 at the end points of its movement until positively moved. Lever 55 has a roller 55', or another type of contact face, adapted, by the travel of the carriage 4, to alternately engage stops or tappet members 32 and 33 which shift the lever 55, and, with it, lever 5, thereby also shifting the clutch block 47, thereby freeing the grip of one block 46 from the chain 40 and causing the other block 46 to grip the chain. In this manner the carriage 4 is reversely actuated by a chain which continuously moves in the same direction. The stop 33 is carried by the head stock 10 and is adjusted together therewith. Independent adjustment may also be employed if desired.

Secured to carriage 4 and extending across and beneath the lathe bed is an arm 34, engageable by its outer end with the cutter or tool-carrying carriage 3 to drive it. This may be by engaging lugs or pins 35. Any suitable rest period for carriage 3 may be secured by separating the lugs 35 a suitable distance. This has been done for reasons hereinafter disclosed.

The side tools 61 and 62 are fixedly, but adjustably, mounted upon a block 65 which is pivoted at 66 upon a lug or web 3'', which projects from the carriage face. This block 65 is adjustable in position and fixedly held when adjusted through the use of set bolts 69 which screw through lugs extending from the block 65 and engage lugs 3' carried by carriage 3, supplemented by other adjusting bolts 69' which screw through lugs 69'', carried by web 3'' and engage the block 65. These side tools 61 and 62 are thus fixed, but adjustable with reference to the carriage. They serve to reduce the square stock to a cylindrical shape.

The centrally-placed cutting tool 60 is a finishing tool, and is set to make a finishing cut after the roughing tools 61 or 62 have removed most of the stock. That one of tools 61 and 62, which is leading, is the only roughing tool which works at any one time. Tool 62 cuts when the carriage moves to the right hand, as shown in Figure 5, and tool 61 when the carriage moves to the left hand, while

the central or finishing tool cuts when moving in either direction.

The central tool 60 is mounted in definite position with relation to the tool-holding block 6, which is pivoted at 38 upon the carriage 3. A clamping bolt 63 screws through an arm 64 of block 6 upon the tool which is seated upon a face of the block 6. Tools 61 and 62 are held upon their seats by set bolts 67, which screw through yoke arms 68, also pivoted at 66.

A spring 125 mounted upon a bolt or rod 126 anchored at 127 to the carriage base 3 and bearing against a lug 128 carried by the tool-carrying block 6, urges said block with the cutter or tool 60, towards the work. A bar or plate 36 is secured to the lathe bed and has its outer edge shaped to form a cam, adapted, by engagement with a contact member, as 37, carried by the cutter-carrying-pivoted block 6, to swing the latter so as to cause outward and inward movement of the cutter 60 relative to the work being turned. In this manner simple outer shapes may be given to the stick 23 being turned. We have shown the contact member which engages the edge of the cam bar as being a bolt 37 which is readily adjustable for work of different diameters.

At the two points indicated by 7, guideways 30 are provided for receiving the ends of the blanks or sticks which are to be turned. These function to a certain extent as a hopper, or feed chute, as they would usually be made of a size to hold at least three or four sticks, and 35 might be made larger. A hopper may be provided for delivering stock thereto.

The size of these stock guides is variable to correspond with variation in size of stock. The construction illustrated for doing this is 40 as follows: The outer or end wall 70 is fixed, except as adjustment may be made for longer or shorter stock. The side members 71 and 72 are adjustable towards and from each other, in a symmetrical relation. The end wall 70 has 45° inclined slots 73, and the bars 71 and 72 have supporting and guiding pins entering 45 said slots. Pivoted at 74 upon the outer face of the end wall 70 is a bar 75, each end of which has a pin which passes through suitable 50 slots 73 in the wall 70 and engage, respectively, with the bars 71 and 72. By reason of the inclined slots and the pins therein carried by the bars 71 and 72, rocking of the bar 75 causes a symmetrical movement of separation 55 or approach between bars 71 and 72. Bar 75 may be secured in adjusted position, thereby holding bars 71 and 72 in exact position.

Cooperating with the above hopper or guide chute is a feeding or transfer mechanism, by 60 which a blank is transferred from the hopper to a position to be engaged by the lathe centers. This mechanism employs a transfer bar or plate 76 held in guides which permit reciprocation transversely of the lathe bed. Similar transfer mechanisms are employed at each

end of the stock, one carried upon the head stock and the other upon the tail stock. The slide 76 has an upstanding longitudinal rib 77, and this supports a shoe 8 and a plate 80 mounted for adjustment thereon. Shoe 8 has a vertical end surface 81 and plate 80, a finger having a horizontal upper face 82 extending beyond the end 81. These two surfaces, 81 and 82, engage respectively with the outer vertical and with the under faces of the stick to be turned, to thereby accurately position it for placing between the lathe centers.

The rib 77 carries guide pins 78 and the parts 8, and 80 have 45° inclined slots into which said pins extend. A right-and-left threaded bolt 83 is anchored by its head 83' in a slot formed in rib 77, that is, upon the slide 76. Its threaded sections engage, respectively, with portions 8' and 80' of the two parts 8 and 80.

It is evident that turning of the bolt 83 will uniformly and equally move said parts 8 and 80 to either separate them or bring them together, depending upon the direction of turning. This will cause the stock-positioning faces 81 and 82 to move a like amount, thereby maintaining the central axis of the stock so placed for all sizes of stock, that it occupies exactly the same position with reference to the feed slide 76 when the latter is at its innermost or stock-delivering position, said axis then coinciding with the axis of the turning centers 13 and 14.

The stock-feeding slide 76 is moved transversely of the lathe bed through the rocking action of a shaft 85 transmitted through arm 84 and link 86. Link 86 is provided with an adjustable-length section 87 which screws into it, and a spring 88 to provide resiliency. The inner ends of slides 76 are each provided with a yielding retaining-finger 89 pivoted thereon and normally held in retaining position by a spring 89', so that it will yield to pass under the stick S when the stick is engaged by the centers 13 and 14, and the slide 76 is withdrawn.

The carriage 4, which is the driving carriage, has guideways extending transversely of the lathe bed in which are slides 90 of a cam-carrying plate 9. This plate is given periodic and limited movement transversely of the direction of travel of the carriage 4. It has two cam rollers 91, one at each side edge, and two sets of two cams each, represented by 95 and 96. The particular portion of the latter cams, indicated by 95 and 96, are the inclined surfaces or cams proper, while the surfaces 95' and 96' are flat level surfaces, and 96'' are short sections at an intermediate level. The elevational outline of these cams is plainly shown in Figure 2, and their plan position in Figure 7.

It will be seen that each type of cam, as 95 and 96, is in duplicate, and that the in-

clined or cam surfaces of like cams face oppositely.

Positioned adjacent to both the head stock and tail stock are a pair of vertically-guided plungers 200 and 202. Their lower ends are provided with cam rollers 201 positioned to be engaged by the cams 95 and 96. Plunger 200 is actuated by cams 96 and plungers 202 by cams 95. An arm 204 carried by transversely positioned shaft 26 is engaged by roller 203 carried by the upper end of plunger 200. The two shafts 26, one in each head, are connected for simultaneous and like movement by a compound link composed of two bars 29 secured in adjusted relation by any suitable clamping device, as the yoke 29' and a set bolt. Shafts 26 are each equipped alike, except that the one in the tail stock is longer and carries an arm 25 which engages the center-controlling bar 24 to push it back, thereby withdrawing the tail center and releasing the stick which has just been turned. The cam which does this work is the cam 96, which has the two surfaces 96' and 96'' at two separate levels. The turned stick is released during the travel of the roller 201 up the incline 96; the new stick is inserted during the movement over the level surface 96', during which period the tail center is withdrawn, and the tail center is brought up to and partly set into the ends of the next stick as the roller drops to the intermediate level 96'', and moved to a final set as the roller drops off of the level 96''.

The movement of the center caused by the first drop, namely, from surface 96' to 96'', is gaged to cause a preliminary setting of the central cone 13' of the center without engaging the driving bits 13'' which are usually formed upon and are a part of such centers as illustrated in Figure 13. The setting of the driving bits 13'', illustrated in Figure 14, is produced by the dropping of roller 201 off of the level 96'' to the level 9.

During the slight delay between these two drops, the withdrawal of the stock placing mechanism has started and proceeded far enough to cause the finger 89 to be cleared of the stick S. The spring 89' is of a strength such that as the slightly curved outer end of the finger 89 engages the corner of the stick S, it will give the stick a sharp whirling movement. This is possible only because the small point at the axis of the centers have been set and the driving bits are not yet in engagement with the stick.

We have found that without giving the work blank preliminary rotative movement before complete setting up of the centers, the high rotative speed of the driving center will cause it to dig or bore into the end of the blank, before its gets into full rotative movement. In machines built by us we have used a rotative speed of 4000 R. P. M. When the blank

is given a sharp twirling movement before full setting of the centers, we find the driving dog setting properly and without boring into the blank end. We have found this feature to be a strong contributing factor in our successfully using such high rotative speeds. This we believe to be due in large part to giving the blank an advance rotation and in part to setting the centers in two stages or steps. This plan has largely increased the capacity of the machine.

The other cams 95 are employed to feed the blank stock from the supply chute or hopper to the lathe centers. The plunger 202 actuated by the cam 95, has a roller 203 on its upper end which engages a lever arm 205 secured to a shaft 85, which extends lengthwise of and above the lathe bed. This shaft is normally turned to press the plunger 202 downwardly by a spring 207 acting upon another crank arm 206. Shaft 85 has two downwardly-extending arms 84, previously described, which actuate the stock-feeding mechanism. As the cam 95 comes into action the slide 76 is advanced to place a new blank S between the centers.

The action of these cams follows immediately after beginning a stroke of the carriage 4. The transverse position of the cams 95 and 96 is such that as they approach the end of a carriage stroke or travel, they occupy paths which do not include the rollers carried by the plungers 200 and 202. Just after passing these rollers, a roller 91 at one side engages the fixed cam incline 93 to shift the slide plate 9 laterally to bring the cams 95 and 96 into alignment with the plungers 200 and 202. After actuation of these plungers, the roller 91 at the other side of the plate 9 engages the fixed incline 94 to shift the plate back again. This mechanism is duplicated at the other end of the path of travel of the carriage. The sets of cams 95 and 96 at each end of slide 9 act upon the plungers 200 and 202 located at the corresponding end of the travel of the carriage and not upon those at the other end.

The mechanism previously described will finish-turn sticks which do not have circular ring or valley shapes, or circular shapes of sharp contour. When such shapes are desired, the finishing steps of shaping must be done by an attachment, of which we have shown a simple and practical form in Figures 3, 4 and 5. This is preferably assembled as an entirety upon a base or frame of its own so that it may be removed entirely when not needed.

Upon the frame bar 100, which, as illustrated, is of U-shaped cross section, although this section is not a material feature, is secured a cam plate or plates 103 and 104, these having acting surfaces positioned and shaped to conform to the necessities of each particular case. The cam plates 103, 104 are secured

to a plate 106 which is mounted to slide lengthwise of the lathe bed in guides carried by the arms 101 and 102 of the bar 100. This plate is actuated by two arms 107 which are fixed thereto and extend into the path of travel of a lug 108 carried by the main tool-carrying carriage 3. The separation of arms 107 is determined in conformity with the extent of the rest period of carriage 3, due to the separation of the lugs 35 by which the carriage 3 is driven.

Mounted for vertical reciprocation in bar 100 are tool holders which carry special shaping cutters which are forced down upon the work by the cam in passing. These tool holders 110 have their upper portions bored and a slot 113 in one side wall. Mounted in this bore is a cylinder 112 which is axially bored to receive the clamping bolt 116, which 20 has its lower end anchored in the plunger or tool carrying cylinder 110, and is provided with an adjusting nut 114 at its upper end. The sleeve 112 has a lug or pin 118 projecting through slot 113 and carrying cam roller 25 115, which engages the cam 103 to thereby force the tool-carrying plunger 110 downward.

Secured to the lower ends of the plungers 110 are shaping tools 120 which have cutting edges shaped to conform to the shape desired to form upon the stick. Figure 2 shows the shaped cutting edges by the curved lines 121. These may be varied in shape at will. The tool-carrying plungers 110 are raised by 30 springs 122 which connect pins carried, respectively, by the frame 100 and by the rear end of the tool 120, or by some other part carried by the plunger 110. To prevent a failure in the upward movement of the 35 plungers 110, or to prevent downward movement thereof beyond that defined by the cam 103, a cam 104 may be placed to engage the lower face of the roller 115. To insure a constant position of the plungers relative to 40 their axes, they are provided, together with their guiding sockets, with a tongue and groove construction, as indicated at 111 in Figures 2, 3 and 4. These special shaping heads are to be used in conjunction with the 45 rough turning means carried by the carriage 3. Special heads for special jobs are contemplated, these being secured so as to be easily removed and substituted, as by 50 bolts 105.

To drive this machine, we have shown two 55 motors as used. The motor 18, through change gear pulleys 16 and 15, and a connecting belt 17, drives the lathe centers, while another motor 400, through a belt 401 and 60 suitable speed reducing mechanism, not shown, drives the chain 40 which moves the carriage and controls the operation of the parts of the lathe.

What we claim as our invention is:

65 1. The method of operating high speed

turning lathes which consists in first lightly setting the centers in and to support the blank for rotation followed by a pause in the setting movement of the centers, giving the blank a twirling movement during said pause and by means independent of the action of the centers, and then completing the setting of the centers.

6 2. In a turning lathe having work holding centers, a center setting means employing a stepped cam having a central dwell period and means operated during said dwell period to give the stock a rotative movement.

3. The method of placing stock in a wood turning lathe which consists in lightly setting the centers in the ends of the stock without engaging the driving bits, imparting a turning movement to the stock by means independent of the centers and then setting up the centers to set the driving bits in the stock.

Signed at Seattle, King County, Washington, this 27th day of May, 1927.

FRED M. GILMORE.
STEVE FRENCH.
